UNITED STATES PATENT OFFICE.

EDWARD S. ANDERSON ENDREA, OF CHICAGO, ILLINOIS, ASSIGNOR TO WATERPROOF-
ING, INCORPORATED, OF INDIANAPOLIS, INDIANA, A CORPORATION OF INDIANA.

COMBINED SHOE AND ARCH SUPPORT.

Application filed October 3, 1921. Serial No. 505,157.

To all whom it may concern:

Be it known that I, EDWARD S. ANDERSON ENDREA, a citizen of the United States, residing at Chicago, in the county of Cook and State of Illinois, have invented certain new and useful Improvements in Combined Shoes and Arch Supports, of which the following is a specification.

My invention has reference to the construction of shoes with a special arch support therein and relates particularly to the manner of fastening the arch support in the shoe so that it is a permanent part of the latter.

It frequently occurs that peculiarities in a person's foot render it desirable to provide a special support in the shoe to fit a high arch or to overcome a tendency of the foot to lean toward one side or the other of the shoe, and it has been customary in such cases, to merely place the necessary arch support in the finished shoe and fasten same in place by means of cement or small nails.

The principal objects of my invention are to construct the shoe with the arch support therein so that the shoe is fashioned to properly fit around the arch support; to construct the arch support as a permanent part of the shoe; to fasten the arch support in the shoe in an improved manner so that the flexibility of the arch support is not impaired and in general, to provide an improved shoe construction which is better adapted to accommodate or compensate for peculiarities of the feet than have been heretofore provided.

On the drawings,

Fig. 1 is a side view of a shoe last having an in-sole and arch support applied thereon in accordance with my invention preparatory to the making of the shoe;

Fig. 2, a bottom view of the construction shown in Fig. 1;

Fig. 3, a top view of the arch support with parts broken away and showing a portion of the in-sole to which it is attached;

Fig. 4, a side view of a shoe constructed in accordance with my invention and showing the in-sole and arch support therein in dotted lines, and

Fig. 5, a sectional view on the line 5—5 of Fig. 4.

Referring to the drawings the reference numeral 1 indicates as a whole an arch support, which is similar to that shown and

described in U. S. Letters Patent No. 988,942 of Apr. 11th, 1911, to Krech et al. and consists of superposed layers of flexible material preferably leather of increasingly smaller size which are secured together by stitching along the line 2, so that each layer while independently flexible is held in the required relative position with reference to the other layers. In my present invention this arch support 1 is secured to the in-sole 3 of the shoe, by a line of stitching 5 passing through the lower layer 4 of the arch support and the in-sole and located preferably just under the edge of the second layer 6 of the arch support, as shown in Figs. 3 and 5. To attach the arch support to the shoe in this manner, a last 7 is gouged out or cut away to afford a recess in which the arch support 1 fits when the in-sole 3 with arch support attached is placed in the proper position on the last and this in-sole with the arch support sewed thereto along the line 5, is then tacked onto the last by means of a number of small nails 8. The shoe upper is then fitted over the last 7 in the usual manner and the edges thereof turned over the in-sole 3 and secured thereto, after which the tacks or small nails 8 are removed so that the last is free to be removed from the shoe when the latter is completed. The shoe sole is then applied over the in-sole 3 and the shoe completed in the usual manner, after which the last 7 is removed leaving the shoe with the in-sole 3 formed as a part thereof and the arch support 1 firmly attached to the in-sole.

By constructing the shoe in this manner the parts of the shoe are caused to fit snugly around the arch support and the latter is securely fastened in the proper position so that there is no danger of displacement of the arch support and the flexibility of the latter is in nowise impaired by the connection thereof to the shoe.

It is to be understood that the arch support shown and described is merely exemplary and that the invention is not confined to the particular form shown but the arch support may be in any form that the peculiarity of the foot requires and the last 7 in each case is formed to correspond with the particular arch support.

While I have shown and described my invention in a preferred form, I am aware that various changes and modifications may

be made without departing from the principles of my invention, the scope of which should be determined by reference to the appended claims.

I claim as my invention:

1. The improvement in the art of manufacturing a shoe to fit the arch of the foot which consists in first applying to the last an in-sole having an arch supporting member permanently secured thereto at one side and loose from and projecting beyond the other side of the in-sole, then applying the shoe upper and the sole and finally removing the last from the completed shoe.

2. The improvement in the art of manufacturing a shoe to fit the arch of the foot which consists in first forming a shoe last with a recess to accommodate the desired arch support and attaching the arch support to and at a distance from the lateral edges of the in-sole of the shoe which is to be con-

structed on the last, then applying the combined in-sole and arch support to the shoe last so that the arch support fits in the recess provided therefor in the last, then 25 temporarily attaching the in-sole to the last, then applying the shoe upper onto the last and securing same to the in-sole, then releasing the in-sole from the last and stitching the shoe sole to the in-sole along the 30 edges of the latter so that the arch support loosely overlies said stitching and then removing the last from the completed shoe.

3. In a shoe the combination with the in-sole of an arch supporting member sewed 35 to the in-sole along one edge thereof and loose from and projecting beyond the other edge of the in-sole, said member comprising a plurality of layers of flexible material secured together at a distance from the point 40 of attachment of said member to the in-sole.

EDWARD S. ANDERSON ENDREA.
